UNITED STATES PATENT OFFICE.

LYTAL M. FELTS, OF BALTIMORE, MARYLAND.

LEAF-SPRING.

1,146,318.

Specification of Letters Patent. Patented July 13, 1915.

Application filed June 3, 1913, Serial No. 771,452. Renewed November 17, 1914. Serial No. 872,650.

To all whom it may concern:

Be it known that I, LYTAL M. FELTS, a citizen of the United States, residing at Baltimore, State of Maryland, have invented 5 new and useful Improvements in Leaf-Springs, of which the following is a specification.

The invention has relation to built up springs comprising a plurality of leaves or 10 plates arranged one upon the other, and has for its object to provide a spring of the type aforesaid possessing great elasticity, thereby resulting in easy riding, and furthermore providing a spring which is practically 15 noiseless and capable of being lubricated and to retain such lubrication without permitting the same to escape and collect dust or cause the spring to assume a besmeared appearance.

20 The invention consists of the novel features, details of construction and combination of parts, which hereinafter will be more particularly set forth, illustrated in the accompanying drawing, and pointed out in the 25 appended claim.

Referring to the drawing, forming a part 30 of the specification, Figure 1 is a side view of a semi-elliptic bow spring embodying the invention. Fig. 2 is a central longitudinal 35 section of the spring. Fig. 3 is a transverse section on the line $\alpha-\alpha$ of Fig. 1. Fig. 4 is a detail view of one of the leaves or plates of the spring.

Corresponding and like parts are referred 40 to in the following description, and indicated in all the views of the drawing, by the same reference characters.

The invention is applicable to the type 45 of springs embodying a plurality of leaves or plates 1, which have a superposed arrangement, such springs usually being of the semi-elliptical or bow type, as indicated most clearly in Figs. 1 and 2 of the drawing. The leaves or plates 1 of the spring progressively decrease in length and each of such leaves or plates 1 is of similar formation, the same tapering from a middle point toward the extremities.

The essential feature of the invention 50 resides in the provision of a recess in each end portion of a leaf or plate to provide a space adapted to receive and hold a lubricant, whereby the leaves or plates are adapted to

move freely one upon the other in the operation of the spring when subjected to vertical thrusts. The middle portions of the leaves or plates are of uniform thickness transversely so as to rest firmly upon one another and admit of the plurality of leaves or plates being bound together by means of a clip or in any manner usually provided. The recess 2 is practically of uniform width throughout its length, the inner end portion tapering and vanishing into the side of the leaf or plate provided with such recess. The 55 marginal portion 3 inclosing the recess 2 is of a width to insure a substantial bearing portion between the several leaves or plates so as to sustain the strain when the spring is in active service.

It is observed that the invention results in the provision of a leaf spring having the terminal portions of the leaves or plates formed with recesses which are adapted to receive and hold a lubricant, whereby the 60 extremities of the leaves are adapted to play freely upon one another when the spring is in operation, with the result that the elasticity of the spring is increased, the 65 easy riding qualities enhanced and noise 70 prevented by the rubbing of the leaf terminals upon one another.

Having thus described the invention what is claimed as new, is:—

A spring comprising a plurality of leaves 80 or plates of uniform width arranged one upon the other and having their middle portions of uniform thickness so as to touch throughout their length, the end portions of the leaves having recesses formed therein 85 which result in the provision of spaces between adjacent leaves or plates to receive and contain a lubricant, said recesses tapering toward their inner ends and vanishing into the sides of the leaves in which the 90 recesses are formed, and the marginal portions of the leaves at the sides and ends of the recesses touching to sustain the load and 95 retain the lubricant.

In testimony whereof I affix my signature in presence of two witnesses.

LYTAL M. FELTS.
